UNITED STATES PATENT OFFICE.

JAMES NOXON AND THOMAS H. NOXON, OF INGERSOLL, ONTARIO, CANADA.

SPRING-HOE FOR GRAIN-DRILLS.

SPECIFICATION forming part of Letters Patent No. 258,465, dated May 23, 1882.

Application filed December 22, 1881. (Model.)

To all whom it may concern:

Be it known that we, JAMES NOXON and THOMAS H. NOXON, both of Ingersoll, in the county of Oxford, in the Province of Ontario, 5 Canada, have jointly invented certain new and useful Improvements in Spring-Hoes for Grain-Drills; and we do hereby declare that the following is a full, clear, and exact description of the same.

10 This invention relates to the spring-hoes of grain-drills, and has for its object to adjust the rigidity of the hoe to suit various conditions of the ground in which it works, and to yield to pass over foreign obstructions and automatically resume its normal position for drilling. The improvement also effects a saving 15 in the cost of manufacture as compared with hoes of a like class.

Our invention consists in the combination, 20 with the drag-bars and hoe of a grain-drill, of links pivoted to the fin of a hoe or to an intermediate connecting-plate, a rocking cylinder journaled in line with said links, which connect therewith by a fixed crank-arm on said 25 cylinder, a spring wound around said cylinder, the free end of the spring attached thereto and the other end to a fixture on or in connection with the draft-bars, and an eccentric having a face locking with the end of a cylinder, which 30 is clamped between the drag-bars, said eccentric having connection with an arm of the rocking cylinder, so that by the adjustment of the eccentric to raise or lower the arm of the cylinder a variable lock of greater or less rigidity 35 is maintained by the aligned position of the pivotal connections to resist the impact of the hoe striking an obstruction, and after such impact yield to pass over the obstruction, the spring then closing around its cylinder, which 40 is rocked by the yielding of the hoe, and reacted by the expansion of the spring to restore the hoe to its normal position for drilling.

Figure 1 is a side elevation of the drag-bars and hoe of a grain-drill, showing the rocking 45 cylinder, spring, connecting-links, and adjusting devices. Fig. 2 is a sectional elevation of the same, showing the yielding movement of the hoe and connecting parts in dotted lines. Fig. 3 is a top view, and Figs. 4 and 5 are 50 tail views.

A A are the parallel drag-bars; B, the hoe having fin C; and D, a plate pivoted thereto

and clamped by a bolt and nut passing through a curved slot, whereby the pitch of the hoe can be regulated. In practice we may dispense 55 with the plate D in carrying out our present invention, as it is not essential thereto.

F F are parallel links pivoted at one end to a forward projection, E, on plate D, or fin C when the former is not used, and to the lower 60 part of said plate D or fin C the drag-bars A A are pivoted by a bolt, P, which constitutes the fulcrum of movement of the hoe. H is a rocking cylinder axially journaled between the drag-bars A A, and is connected pivotally 65 to the lower ends of links F F by a lug, G, the pivotal connection being approximately in line to the axis of cylinder H and the upper pivotal connection of bar F with the hoe, whereby a locking of the parts results, which is broken 7 by throwing them out of line, in which case the links F F will bear down the lug G to a crank position, as shown in dotted lines in Fig. 2, and which position is assumed when the hoe is passing over an obstruction.

J is a spring wound spirally around the cylinder H. The free end of the spring is secured to a lug, I, projecting from said cylinder at one end. The opposite end of the spring is fastened to lug K on a flanged projection, M, 80 which forms part of a fixed cylinder, L, axially secured between the bars A A, and which cylinder-projection and lug confine the end of the spring fixedly, whereby when the free end of the spring is compressed around the cylinder 85 the tension of the spring is distributed throughout its whole length, so that when it reacts by expansion the spring rocks the cylinder H, and thereby draws the hoe to its normal position after it has passed an obstruction. At the 90 opposite end of cylinder L is placed axially therewith an eccentric, O, which is provided with a serrated face locking with a corresponding face on the end of cylinder L, said eccentric forming a stop for an arm, N, integral 95 with the cylinder H, so that by adjusting the eccentric the arm N will be raised and lowered to throw the pivot-connection of G and F out of approximate alignment with the axis of cylinder H and pivot-connection of F and D, 100 whereby the resistance of the hoe to an obstruction will be weakened or strengthened at the impact according to the distance at which said central pivot may be set by the adjust-

ment of the eccentric on its axis. After the impact of the hoe with its obstruction has overcome the resistance the hoe will yield to pass over the obstruction by the compression of the spring around its cylinder by the depression of the links F F, causing the cylinder H to rock, and when the spring expands the cylinder is reacted, and thereby draws the hoe to its normal position after it has passed the obstruction.

We are aware that volute coiled springs and spiral-spring coils having an endwise tension have been used to retain the hoe and allow it to yield to pass over an obstruction; but these do not possess sufficient rigidity combined with retentive power to meet requirements suited to the variable condition and character of the ground in which the drill is worked.

We claim as our invention—

- 1. In a grain-drill, the combination, with the hoe B and drag-bars A A, of a rocking cylinder, H, axially journaled between the drag-bars, spring J, wound spirally around said cylinder, the free end secured to a lug, I, of the cylinder, the other end attached to a fixture, links F F, pivoted to a lug, G, of the cylinder, and to a plate, D, or fin C of the hoe above the pivot-point of its connection with the drag-bars, and eccentric O, forming a stop for an arm, N, of cylinder H, whereby

the primary resistance of the hoe to an obstruction can be weakened and strengthened by throwing the pivotal end of links F F more or less out of line with the axis of cylinder H by the adjustment of the eccentric O, raising 35 and lowering the arm N, the spring J reacting to retract the hoe to a normal position after yielding to and passing over an obstruction, as set forth.

2. In combination with a cylinder, H, journaled between the drag-bars of a grain-drill, and spring J, wound spirally around said cylinder, the cylinder L, axially secured between the drag-bars by a clamping-bolt, and provided with interlocking faces, for the purpose set 40 45 forth.

3. In combination with spring J, wound around a cylinder, H, journaled between drag-bars A A, pivoted to the hoes B or plate D, and connected to the hoes by links F F, the cylinder L, axially secured between the bars A A, and having a flange, M, and projection K, to secure the end of spring J fixedly, as set forth.

JAMES NOXON.
